UNITED STATES PATENT OFFICE.

PERCY R. SEAMON, OF BOSTON, MASSACHUSETTS, ASSIGNOR TO PORTLAND SALES COMPANY, OF BOSTON, MASSACHUSETTS, A CORPORATION OF MASSACHUSETTS.

DESIGN FOR A MIRROR-STAND.

47,863.

Specification for Design.

Patented Sept. 21, 1915.

Application filed May 22, 1913. Serial No. 769,304. Term of patent 7 years.

To all whom it may concern:

Be it known that I, PERCY R. SEAMON, citizen of the United States, residing at Boston, county of Suffolk, State of Massachusetts, have invented a new, original, and ornamental Design for a Mirror-Stand, of which the following is a specification, reference being had to the accompanying drawing, forming part thereof.

0 The figure is a perspective view of the mirror stand of applicant's design which comprises a curved arm A circular in cross section having the inturned ends B, said curved arm A being held in position in a fastening device C by means of the set screw D,

the fastening device C having a flat disk like member E which is secured to a base portion or supporting member F by means of a screw G.

I claim:

20 The ornamental design for a mirror stand as shown and described.

In testimony whereof I have signed my name to this specification in the presence of two subscribing witnesses.

PERCY R. SEAMON.
